ABSTRACT OF THE DISCLOSURE

A device for mooring ships offshore, in particular for the transportation of liquids between a ship and the shore, having an upright mast structure rising from the sea bottom to the surface and anchored at its lower end for universal swinging movement and free rotation about its longitudinal axis, the mast structure carrying floats keeping the same in its upright position. A mooring boom is secured to the mast structure below the water level and extends sideways therefrom in a horizontal position which boom carries one or more mooring towers provided with floats and rising upwardly therefrom to a suitable height above the water level. A riser pipe runs upwardly through the mast structure being connected at its lower end to a pipeline running to the shore and being coupled at its upper end to a pipe running through the mooring boom and towers for connection with the pipe system of a ship.

BACKGROUND OF THE INVENTION

The invention relates to a device for mooring ships offshore, in particular for the transportation of fluid materials, such as oil between a ship and the shore.

The present trend in modern shipping of building tankers for the transport of oil and similar products of ever increasing tonnage has raised the problem that in many cases existing harbour facilities are not adapted to receive and handle such large tankers, and therefore make it necessary to load and discharge these ships offshore. For that reason it has been suggested to mount a terminal platform or similar structure on the sea bottom some distance offshore, which platform is connected by one or more submerged pipelines to suitable shore installations, such as storage tanks, and is provided with one or more flexible hoses for connection to the tankers to be loaded or discharged, which hoses may float on the surface or may be submergeable. Generally, during operation of this known arrangement the ships are moored to mooring buoys arranged in the vicinity of the terminal platform.

SUMMARY OF THE INVENTION

The invention has for its main object to provide a device for mooring ships offshore, which may replace the conventional mooring buoys and which at the same time can be adapted for use as a terminal for loading and unloading fluid materials, such as oil. More in particular, the invention has for its object to provide such a mooring device allowing a quick and efficient mooring and loading or unloading of ships, also in case of a rough sea.

The mooring device of the invention generally comprises a mast structure rising from a fixed base member on the sea bottom to the water surface and pivotally anchored at its lower end to this base member for universal lateral swinging movement and for free rotation about its longitudinal axis, the mast structure comprising one or more floats or buoyancy chambers adjacent its upper end tending to keep the mast structure in a vertical position. A mooring boom is secured to the mast structure extending sideways therefrom and likewise comprising

2

float means supporting the boom in a substantially horizontal position. The mooring boom is preferably attached to the mast structure at a distance below the water level, the boom carrying one or more mooring towers rising upwardly therefrom to a suitable distance above the water surface and comprising the boom floating means. The mooring boom can be rigidly secured to the mast structure but preferably the boom is secured to this structure by suitable coupling means allowing the boom to swing relative to the mast structure in a substantially vertical plane through the axis of the mast structure.

The mast structure with the mooring boom connected thereto is thus free to rotate about its longitudinal axis whereby the mooring boom can at all times assume a position in accordance with the prevailing currents. The buoyancy chambers of the mast structure provide an effective stabilizing force in that on a tilting movement of the mast structure with respect to the vertical caused by an external force, these chambers or floats produce a counteracting moment which increases with an increasing deviation of the mast structure from its vertical position. The shock forces exerted on the device by a ship mooring thereto are thus yieldingly and efficiently damped by a tilting movement of the mast structure and by a swinging movement of the mooring boom about the vertical axis of the mast structure.

The mast structure and the mooring boom may each form at least partly an open frame structure with closed hollow structural members, which thus contribute to the buoyancy of these parts.

According to a preferred embodiment of the invention, a fixed rigid riser pipe extends vertically upwardly from the sea bottom centrally through the mast structure, which riser pipe is connected at its lower end to a pipeline running to the shore and is connected at its upper end above the water level through a horizontal swivel pipe coupling and a flexible hose to a pipeline extending longitudinally through the mooring boom. This pipe line may be provided with one or more suitable coupling means for connection to a flexible line leading to a moored ship. The mast structure thus forms a kind of protecting cage about the riser pipe, and the swivel pipe coupling at the upper end of the rigid pipe is easily accessible for maintenance and inspection.

BRIEF DESCRIPTION OF THE DRAWINGS

The present invention will be more readily understood and the further objects and advantages thereof will be more apparent when read in conjunction with the accompanying drawings in which

FIG. 1 is a side elevational view of an embodiment of the device according to the invention;

FIG. 2 is a sectional view as seen on the line II—II of FIG. 1;

FIG. 3 is a sectional view as seen on the line III—III of FIG. 1;

FIG. 4 is on an enlarged scale an elevation and partly a section of the pivotal mounting assembly for anchoring the mast structure of the device of FIG. 1—3 to the sea bottom;

FIG. 5 is a perspective view of a part of another embodiment of the invention, showing the coupling arrangement between the mast structure and the boom; and

FIG. 6 is a cross-sectional view of one of the buffer elements of the device of FIG. 5.

PREFERRED EMBODIMENTS OF THE INVENTION

Referring to FIG. 1—3 of the drawings, the mooring device of the invention has as its main components a mast structure 3 rising from the sea bottom 1 to the

water level at 2, and a mooring boom 4 extending substantially horizontally sideways from the mast structure 3 and carrying two mooring towers 5 and 6 rising from this boom to some distance above the water level 2. The mast 3, the boom 4 and the towers 5 and 6 are carried out as open frame structures of closed hollow tubular members welded together and filled with air.

The mast structure 3 has a downwardly tapering shape is shown and is anchored at its lower end to a foundation block 7 on the sea bottom 1 for universal lateral winging movement and for free rotational movement about its longitudinal axis. The mast structure has four corner posts 8 extending upwardly and outwardly from the anchored lower mast end and carrying two buoyancy chambers 9 at the wide upper end of the mast, which chambers are arranged at two opposite sides of the mast structure. The buoyancy chambers extend partly above the water level 2 and are so dimensioned and arranged that they exert at all times an upwardly directed force in the mast structure, also at the lowest water level 0 to be expected, and thus try to maintain the mast structure in a vertical position.

The mooring boom 4 is arranged some distance below the water level. In the embodiment shown in the drawing, the boom is secured to the mast 3 midway of the height of the latter by means of a hinge connection 10 with horizontal pivot axis. The boom 4 has a triangular cross-sectional shape with two upper longitudinal girder members 11 and a lower longitudinal girder member 12. The mooring tower 5 is arranged at a distance from the mast 3 of about one-third of the length of the boom and the mooring tower 6 is arranged at the free outer end of the boom. The towers 5 and 6 have a lateral width gradually increasing from the boom upwardly, as shown in FIG. 3, and each carry at their upper end a platform 13 and 14, respectively, spaced at a suitable distance above the water level. As appears from FIG. 1, the tower 5 rises vertically upwardly and the tower 6 leans slightly upwardly and away from the mast 3. Two buoyancy chambers 15 are secured to each tower and are so dimensioned that these four buoyancy chambers together can support the weight of the mooring boom 4 and the two towers 5 and 6. For a better stability the two buoyancy chambers of each tower are oppositely arranged at the sides of the tower running parallel to the boom 4 and, to the same purpose, ballast weights 16 are secured to the boom 4 beneath each tower for moving the center of buoyancy of the mooring boom assembly to a point below the center of upward pressure. These weights consist of U-shaped tubes filled with concrete. The mooring boom assembly is so balanced that in the state of equilibrium practically no vertical forces occur in the hinge connection 10, the mooring boom extending substantially horizontally from this hinge connection away from the mast.

Resilient fenders 17 are arranged along the sides of the platforms 13 and 14. If desired, also the upper side of the mast structure 3 with the buoyancy chambers 9 can be protected by similar fenders.

A rigid riser pipe 18 extends vertically upwardly from the foundation block 7 through the mast structure 3 and as a bend at its lower end passing through the block 7 in connection with a pipeline 19 running along the sea bottom to the shore. The riser 18 extends upwardly past the upper end of the mast 3 and is connected at its upper end, by means of a swivel pipe coupling 20, to a U-shaped laterally extending pipe section 21 which can thus rotate in a horizontal plane. Two posts 22 on the buoyancy chambers 9 and slack cables 23 connect the pipe section 21 to the mast structure 3 whereby the pipe section is made to follow the rotary movements of the mast structure about its axis and thus is maintained in a position extending substantially in the same direction as the mooring boom 4. Obviously, other means may be used for keeping the pipe section 21 in the general direction of

the boom 4 if only the pipe section has sufficient room for lateral play to allow for lateral swinging movements of the mast structure. A flexible hose 24 connects the outward end of the pipe section 21 to a rigid pipe section 25 fixedly mounted on the mooring boom 4, which pipe section 25 runs downwardly for connection to the lower tubular girder 12 of the boom structure, this girder thus forming part of the pipe line system. This hollow girder 12 is connected at its outer end with one of the upwardly extending tubular structural members 26 of the mooring tower 6 which tube 26 leads to the platform 14. A pivotal structure 27 is mounted on this platform and a number of hoses 28 are suspended from this portal which hoses are each connected to the pipe line 12, 26 so obtained and are provided with pipe couplings for connection with the pipe system of a ship to be loaded or discharged. Obviously, in a similar way a branch line may be run from the hollow girder 12 through the tower 5 to the platform 13 (not shown). A tanker may thus moor to the platforms 13 and 14 and may be loaded or discharged through the above described pipe line system running through the riser 18, the boom 4 and one or both of the towers 5 and 6.

FIG. 4 shows the pivotal mounting assembly for securing the tapering lower end of the mast structure 3 to the foundation block 7. The concrete block 7 has a circular circumferential shape and is mounted on a circular row of foundation piles 29 arranged in the bottom 1. The block 7 carries a steel base plate 30 with an annular upper structure 31 having an inwardly projecting annular flange 32 at its upper side. This upper structure 31 is secured to the block 7 by bolts (not shown) and may consist of a reinforced concrete structure with a metal shell at its inner side. The base plate 30 carries a circular rail track 33 and the flange 32 carries at its lower side a similar circular rail track 34 having the same diameter as the track 33 and arranged coaxially with the latter. A circumferential rail track 35 is secured to the cylindrical inner wall or metal shell of the annular upper structure 31, said track 35 projecting radially inwardly from this inner wall. An annular carriage 36 is arranged in the space enclosed by the upper structure 31 which carriage comprises a number of rollers 37 journaled on circumferentially spaced shafts radially extending from the annular carriage 36. The rollers 37 are enclosed between and run on the tracks 33 and 34 and allow the carriage to rotate about its vertical axis. The carriage is provided at its circumference with a further set of rollers 38 journaled on vertical shafts and positioned in a common horizontal plane which rollers 38 run on the rail track 35 and thus hold the carriage against radial displacement.

The carriage 36 has two diametrically opposed vertical supports 39 between which a hinge ring 40 is mounted for pivotal movement about a horizontal pivot axis 41 which intersects the vertical axis of the carriage. The hinge ring 40 is likewise provided with two upwardly projecting supports 42 between which a carrier ring 43 is mounted for pivotal movements about a pivot axis 44 which extends perpendicularly to the pivot axis 41 and likewise intersects the vertical axis of the carriage 36. The upwardly extending corner posts 8 of the mast structure 3 are welded to the upper side of this carrier ring 43. The above described pivotal mounting assembly thus allows the mast structure 40 to rotate about its longitudinal axis by means of the rotatably mounted carriage 36, and to make limited swinging movements with respect to the vertical by means of the pivotally mounted intermediate hinge ring 40 and carrier ring 43. In case larger swinging movements of the mast structure are desired than the schematical showing of the assembly of FIG. 4 would allow, it is of course possible to increase the vertical spacing between the parts 36, 40 and 43, respectively.

As shown in FIG. 4, the rigid riser 18, passing with a bent portion through the foundation block 7, extends vertically upwardly along the axis of the carriage 36 and

thus centrally through this carriage and the two rings 40 and 43.

As appears from FIG. 3, a ship 44 can be moored alongside the mooring boom 4 by means of bollards 45 or the like arranged on the platforms 13 and 14. On account of the rotatable mounting of the mast structure 3, the mooring boom 12 with the ship moored thereto is free to swing in a horizontal plane to an angular position in which it extends in the direction of the current and the waves. The forces exerted on the mooring device are therefore considerably smaller than in the case of a fixedly supported mooring device which must also be able to resist transverse wave and wind forces acting on the side of the ship.

If transverse forces are exerted on the mast structure, for instance when a ship is being moored, the mast structure can yield by a tilting movement in which the buoyancy chambers 9 to one side of the assembly are further submerged and at the opposite side are lifted from the water. Thereby a counter moment is created which increases with the degree of tilting and which efficiently damps the impact forces of the ship.

The mooring device of FIG. 5 is similar to the device of the FIGS. 1-4 except for the way the mooring boom 4 is secured to the mast structure 3. In the embodiment shown schematically in FIG. 5, the boom 4 is connected to the posts 8 on one side of the mast 3 by means of a resiliently yieldable coupling arrangement generally indicated by 46. This coupling arrangement consists of a number of rod-like link members 47-52 each comprising two tubular rods 53 and 54 which are slidably connected by a shock-absorbing buffer element 55 arranged therebetween as shown in greater detail in FIG. 6. The link members 47-52 are each pivotally connected at their opposite ends to the mast 3 and the boom 4, respectively, by means of plural swivel joints generally indicated by 56a-56e which allow the link members to swing freely in all directions with respect to the mast or boom, respectively. These swivel joints may be of any suitable known structure and are, therefore, not shown in detail.

As shown in FIG. 5, the link member 47 extends between the swivel joint arranged at 56a on one of the corner posts 8 of the mast to the swivel joint arranged at 56c at the inner end of the lower boom girder 12. Similarly, the link member 48 extends between the swivel joint arranged at 56b on the adjacent mast corner post 8 to the same swivel joint at 56c on the girder 12. The swivel joints 56a and 56b are arranged at the same locations at the hinges 10 of FIG. 1. The link members 47 and 48 together with a crossbeam 57 between the said corner posts 8 thus form a triangular structure.

The link member 49 extends from the swivel joint at 56a to the swivel joint arranged at 56d at the opposite inner end of the relevant upper girder 11 of the boom 4 and the link member 50 extends from the swivel joint at 56b to the swivel joint arranged at 56e at the inner end of the other upper boom girder 11, the members 49 and 50 together with the crossbeam 57 and a crossbeam 58 running between the upper girder ends forming a quadrangular structure. The link members 51 and 52 are arranged as diagonals of this structure and extend between the swivel joints 56a and 56e, and 56b and 56d, respectively. Trusses 59 fixedly connect the ends of the upper boom girders 11 with the end of the lower girder 12, forming a triangle with the crossbeam 58.

As also shown in FIG. 1, the pipe section 25 connected to the lower boom girder 12 is secured adjacent its upper end to the upper ends of two substantially vertical frame members or posts 60 extending upwardly from the upper boom girders 11, these posts 60 and pipe section 25 together forming an upwardly projecting rigid structural frame portion at the inner end of the boom 4.

As shown in FIG. 5, a further resiliently yieldable coupling arrangement, generally indicated by 61, is arranged at a slight angle to the horizontal between the

5 mast 3 and the posts 60 about midway of the height of the latter. This coupling arrangement 61 is similar to the above described quadrangular structure of the coupling arrangement 46 and comprises as shown link members 62 and 63 extending between swivel joints at 56f and 56h, and 56g and 56i, respectively, and diagonal link members 64 and 65 extending between the swivel points at 56f and 56i, and 56g and 56h, respectively, the swivel joints 56f and 56g being arranged on the posts 8 of the masts 3 and the swivel joints 56h and 56i being arranged on the posts 60.

As shown in FIG. 6, each shock-absorbing buffer element 55 arranged in the link members 47-52 and 62-65 comprises a cylinder 66 closed at one end by a closure plate 67 to which the tubular rod section 53 is fixedly secured, for instance by welding. Approximately midway of its length the cylinder 66 has a second closure plate 68 provided with a central bore which slidably and sealingly receives a piston rod 69 of a piston 70 arranged for sliding movement in the cylinder bore between the plates 67 and 68. At its outer end the piston rod 67 is fixedly secured to the tubular rod section 54 which is telescopically received in the open-ended cylinder portion extending past the plate 68 and thus forming a guide for the rod section 54 in its sliding movements with respect to the cylinder 66.

Coil springs 73 and 74 are arranged in the cylinder chambers on both sides of the piston 70 between this piston and the plates 67 and 68, respectively, which springs tend to maintain the piston in its midposition.

The cylinder chambers enclosed between the piston 70 and the plates 67 and 68, respectively, are filled with a suitable liquid, such as oil, and are connected through a bypass conduit 75 comprising a throttle or control valve 76. The conduit 75 opens into the cylinder chambers opposite the stop members 71 and 72 at the ends thereof. The outwardly turned ends of the rod sections 53 and 54 (not shown in FIG. 6) are each connected to one of the swivel joints 56a-56i as above described with respect to FIG. 5.

When an external force is exerted between the rod sections 53 and 54, the piston 70 will be moved to the right or to the left, as seen in FIG. 6, depending on the direction of this force and against the action of the spring 73 or 74 which is being compressed by this movement. The movement of the piston 70 is damped in a known manner by the oil in the cylinder which is displaced by the piston and is forced to flow from the one cylinder chamber to the other through the bypass conduit 75 and through the adjustable flow restriction formed by the control valve 76. Instead of the bypass conduit 75, one or more small holes may be provided in the piston 70 in a known manner. Instead of oil, another suitable liquid, for instance sea water, may be used in the cylinder. If desired, a further spring may be arranged in the cylinder space enclosed between the outer face of the plate 68 and the inner end of the rod section 54.

The above described resiliently yieldable coupling arrangements 56 and 61 with buffer elements 55 constitute an efficient damping means for absorbing part of the impact energy transmitted to the boom and mast by a ship being moored or by the action of the waves and wind. Thereby the high peak stresses which would otherwise occur in the connection between the mast and the boom are efficiently reduced. Also, this coupling arrangement provides a limited freedom for the mooring boom to rise and fall with the tide while substantially maintaining its horizontal position.

While the invention has been shown and described with reference to specific embodiments thereof, it will be understood that other embodiments may be resorted to.

What is claimed is:

1. A device for mooring ships offshore, comprising a mounting base member arranged on the bottom below a body of water, an upright mast structure extending up-

wardly from said base member to above the water level, means for pivotally anchoring said mast structure at its lower end to said base member for universal lateral swinging movement and free rotational movement about its longitudinal axis, said mast structure comprising first float means tending to keep said structure in a vertical position, a mooring boom extending sideways from said mast structure, and means securing said boom to said mast structure, said mooring boom comprising second float means tending to support said boom in a substantially horizontal position.

2. The device of claim 1, in which said mooring boom is secured to said mast structure below the water level at a distance from the mast structure upper end, said mooring boom further comprising at least one mooring tower extending upwardly therefrom to a selected height above said water level, said tower comprising at least part of said second float means.

3. The device of claim 2, in which said mooring boom is provided with ballast means below said mooring tower.

4. The device of claim 1, in which said mooring boom securing means comprises hinge means allowing said mooring boom to swing with respect to said mast structure in a plane substantially through said longitudinal axis of the latter.

5. The device according to claim 4, in which said mooring boom securing means includes a resiliently yieldable coupling arrangement comprising a plurality of link members extending between said mast structure and the inner end of said mooring boom, and a plurality of swivel joint means connecting said link members to said mast structure and boom, respectively, said link members comprising spring-loaded shock-absorbing buffer members allowing said link members to be resiliently longitudinally extended and compressed by external forces acting on said boom.

6. The device of claim 5, in which said buffer members comprise hydraulic means yieldingly resisting the extension and compression, respectively, of said link members.

7. The device of claim 1, in which said mast structure and mooring boom each consist at least partly of an open frame structure comprising closed hollow structural members.

8. The device of claim 1, in particular for the transportation of fluid materials between a ship moored thereto and the shore, further comprising a fixedly secured rigid riser pipe extending vertically upwardly from said base member centrally through said mast structure and adapted to be connected at its lower end to a pipeline running to the shore, a rotary pipe coupling means mounted on the upper end of said riser pipe above the

water level, flexible conduit means communicating at one end through said pipe coupling means with said riser pipe, a pipeline connected to the other end of said flexible conduit means and running outwardly away from said mast structure through said mooring boom, and pipe coupling means connected to the outer end of said mooring boom pipeline and adapted for connection to an external flexible conduit leading to a ship.

9. The device of claim 8, in which said mooring boom comprises a longitudinally extending tubular structural element, said latter element forming part of said mooring boom pipeline.

10. The device of claim 1, in which said anchoring means for said mast structure comprises a horizontal annular carriage means, mounted in said base member for rotation about a vertical axis, first annular member pivotally mounted on said carriage means for swinging movement about a first horizontal pivot axis, and a second annular member pivotally mounted on said first annular member for swinging movement about a second pivot axis perpendicular to said first pivot axis, the lower end of said mast structure being fixedly secured to said second annular member.

11. The device of claim 10, in which said base member has a cylindrical recess, two spaced circular guide rails of equal diameter mounted coaxially one above the other in said recess and a third circular guide rail mounted in said recess coaxially with said first two guide rails, said carriage means comprising a first group of vertically mounted wheels arranged equally spaced from one another about the circumference of said carriage means and enclosed between said first two guide rails for running therebetween, and a second group of wheels mounted about the circumference of said carriage means in a common horizontal plane and running on said third circular guide rail whereby said carriage means is held in said base member against radial and vertical movement.

12. The device of claim 11, in which said first float means on said mast structure are so dimensioned that the mast structure normally exerts an upward pulling force through said anchoring means on said base member.
